[57] CLAIM

The ornamental design for a combined radio, cassette tape recorder and digital audio disk player, as shown and described.

DESCRIPTION

FIG. 1 is a top, front and right side perspective view of a combined radio, cassette tape recorder and digital audio disk player showing my new design, with the disk and tape holders in open position and the handle up;
FIG. 2 is a front elevational view thereof;
FIG. 3 is a top plan view thereof;
FIG. 4 is a left side elevational view thereof;
FIG. 5 is a right side elevational view thereof;
FIG. 6 is a rear elevational view thereof; and
FIG. 7 is a bottom plan view thereof.

FIG. 1

FIG. 2

FIG. 3

FIG. 4

FIG. 5

FIG. 6

FIG. 7
